PROCESS OF FINISHING KNITTED PILE FABRICS

Filed Feb. 19, 1931

UNITED STATES PATENT OFFICE

DAVID PELTON MOORE, OF AVON PARK, FLORIDA

PROCESS OF FINISHING KNITTED PILE FABRICS

Application filed February 19, 1931. Serial No. 517,042.

The present invention relates to improvements in a process of finishing knitted pile fabrics, and more particularly to a knitted pile fabric as is set forth in my U. S. Letters 5 Patent No. 1,791,741 granted to me February 10th, 1931.

When this fabric has been produced in a machine similar to the machines set forth in my co-pending applications, Serial Nos. 10 398,958, 484,448, 498,818, the rear face of the fabric is spotty and the jersey web formed by the basic yarn or yarns is too visible, and again the fabric is too elastic and will not hold its shape. It was therefore necessary 15 and desirable to treat this fabric to a process that would shrink and "set" the fabric, cause the pile elements where held in by the basic 20 yarns to plate and coat the same, and to, at the same time, not produce a matting of the pile. Several methods of accomplishing this 25 have been employed by me, one in which the fabric in the tubular form just as it leaves the knitting machine is treated, and the other in which the tube is split—that is in knitting one 30 needle at least in the cylinder is dropped to form a straight guide for cutting—and the fabric held taut and flat during the processing. This latter is preferable, as it is desirable 35 to roll the finished fabric similarly to plush and velvets, that is on a reel with the convolutions spaced apart so that the pile does not receive any pressure that would tend to flatten or matt it. Where it is finished in tubular form, the tube prior to reeling it is 40 split and the goods reeled in single layer convolutions.

It is therefore evident that many forms of apparatus may be employed to bring about 45 the desired result, and that such apparatus may be of the vertical or horizontal type, but in order to illustrate one method of carrying out the invention, a horizontal type of machine will be illustrated and described in the accompanying drawing, in which:—

Figure 1 is a top plan view in diagram of the complete apparatus.

Figure 2 is a side elevation thereof, also being diagrammatic.

Figures 3, 4, and 5 are views of details. 50

Referring to the drawing, the numeral 6 designates the two guide rails, each one of which extends upon either side of the machine and are elongated loops, so that the 55 caster frames or hangers 7, disposed equidistantly throughout the full length of both rails, and secured in spaced relation to each other by the two sprocket chains 10, will travel with the chains, as will presently appear. 60

Each caster frame is provided with a caster 65 wheel 8 that engages the track 6, and is provided with an inner terminal 15 to which is attached a pin 16, so that the fabric engaging 70 clip or hook 17, may be rigidly attached to the frame or through the spring 18 resiliently 75 attached to such frame.

In order that the chains 10 may be moved in the direction of the arrows, Fig. 1, there 75 is mounted at the inlet end the two sprocket wheels 11, and at the outlet end the two sprocket wheels 12, there being a chain drive 13 from the motor 14 for driving the wheels 12 and consequently the two wheels 11 and moving the chains with the hangers. 80

Two spaced guide rollers 19—19' over 85 which the fabric F, with the pile uppermost is drawn, and first subjected to a moistening or saturation of the rear face or non-pile side, and so that the moisture does not penetrate the pile, by means of the moistener 20, here shown as an atomizer, but which may employ wet steam, warm or hot water sprayed or atomized, or even applied by rotary brushes from below. Beyond this arrangement are 90 another pair of spaced rollers 21—21', between which is disposed a drier 22, preferably superheated, by steam, so that as the moist web of the fabric passes thereover, the steam from the water in the fabric is driven upward. 95

ly through the pile, and such heater being of sufficient length, and the speed of the movement of the fabric being sufficiently slow to thoroughly dry the fabric before passing the 5 guide roller 21'.

Beyond this treatment point of the apparatus, are two spaced rollers 23—23', between which is an air blast device 24, with two nozzles 25 adjacent the underside of the fabric 10 and directing the compressed air upwardly and through the pile. This is an important step, as it finally sets the pile and removes any loose fibers and prevents the matting of the pile adjacent the web. Where desirable, I 15 also place a suction head 26, whose nozzle is very close to the top of the pile so as to tend to stand the pile on end and to remove loose fibers, the same being so regulated as not to unduly abrade the fibers.

20 Although not always necessary, a brushing action may take place at a point 29 between the heater 22 and the air blast 24, and also in conjunction with the air-blast or previous thereto, a beater 28, operated to strike the 25 underside of the fabric in transit, may with advantage be employed.

Whether the brushing and beating is to take place, is regulated entirely upon the length and character of pile, and the finish 30 desired.

It is also possible to produce "caracul" or "cow lick" effects in the pile by hand or machine brushing the pile from above at point 29.

35 From the foregoing description taken in conjunction with the drawing the operation and process will be fully understood, but briefly stated it is as follows.

When it is desired to shrink the fabric F, 40 in width, the fabric is supported its full length, between the clips 17, of both chains 6, the springs being employed to permit the gradual contraction of the material, as it is moved by the chains in the direction of the 45 upper arrow, or from left to right in Fig. 1. Where a thirty (30) yard piece is operated upon, there is a space of this size between the wheels 11 and the moistener 20, so that the piece can be put in place properly stretched.

50 It is now slowly moved to the right, and is subjected successively to the moistening, drying, (beating and/or brushing), and to the air blast and suction action before it arrives at the space between the air-blast 24 and the 55 wheels 12. When the entire piece has thus been acted upon by the various instrumentalities, it is ready to be removed and reeled in spaced convolutions, or it can be reeled as it is successively released from the clips 17.

60 Where this operation takes place on a horizontal machine, the machine is substantially about 210 feet long, but where it is set up vertically, it is about 100 feet long, and can be arranged more or less zig-zag to economize space. It is also possible to reduce the hori-

zontal machine to about 100 feet, in which event the fabric is attached and detached successively as it is fed upon and removed from the apparatus.

Where the fabric is finished in tubular 70 form, instead of the chains and hangers here illustrated, perforated tubular either circular or flattened members are employed, the same being larger in size at the inlet end and reduced gradually to permit shrinkage toward 75 the outlet end. In this event the fabric is slit when finished and reeled similarly to the flat piece.

When it is desired to maintain the width 80 and to shrink lengthwise of the fabric, the springs 18 are dispensed with and the fabric is attached directly to the terminal 15 of the hangers, the extreme ends of the fabric being attached by the springs 30 to the end bars 31, carried by the chains 6, and such springs give 85 to permit this lengthwise shrinking, while the fabric is firmly held on its longitudinal edges and prevented from shrinking in width.

It is evident from the foregoing that many 90 additional features may be added to improve the appearance of the pile, it being essential, however, to so subject the fabric, that the pile is not matted either due to its being moistened too great or from pressure thereon, by ironing, mangling, and/or folding and rolling tightly.

By this arrangement of apparatus and the process therein set forth the improved fabric, such as set forth in my patent, can be produced of many materials, and made into fabrics for outer and inner garments, blankets, carpets and rugs. 100

It is also apparent that a knitted pile fabric of this type made either upon cylinder 105 rotary knitting machines or straight bed machines may be treated with this process.

What is claimed, as new, is:—

1. A process for finishing a knitted pile fabric, which includes the subjecting of the pile fabric non-pile side down while in a 110 stretched condition and in transit, to a moistening only of the non-pile side, drying the fabric from the non-pile side thereof, and forcing an air blast from below through the fabric. 115

2. A process for finishing a knitted pile fabric as claimed in claim 1, wherein in addition to the air blast, a suction action takes place from above coincident with the air blasting action. 120

3. A process for finishing a knitted pile fabric as claimed in claim 1, wherein the non-pile side is subjected to a beating action following the drying action, and preceding the air blast. 125

4. A process for finishing a knitted pile fabric as claimed in claim 1, wherein the non-pile side of the fabric is subjected to a beating action at a point between the drying and air-blast actions. 130

5. A process for finishing a knitted pile fabric as claimed in claim 1, wherein the non-pile side of the fabric is subjected to a beating and the pile side is subjected to a suction
6 action.

6. A process for finishing a knitted pile fabric as claimed in claim 1, wherein the non-pile side of the fabric is subjected to a beating, while the pile side is subjected to brushing, and also a suction action following the beating action.
10

In testimony whereof I affix my signature.
DAVID PELTON MOORE.
